HERBERT H. HULL, OF CLEVELAND, OHIO, ASSIGNOR TO THE PERFECTION CAP & CAN COMPANY, OF CLEVELAND, OHIO, A CORPORATION OF OHIO.

CLOSURE FOR BOTTLES AND JARS AND METHOD OF AFFIXING SAME.

1,169,828.

Specification of Letters Patent.

Patented Feb. 1, 1916.

Application filed December 13, 1912. Serial No. 736,576.

To all whom it may concern:

Be it known that I, HERBERT H. HULL, a citizen of the United States, and a resident of Cleveland, county of Cuyahoga, and 5 State of Ohio, have invented a new and useful Improvement in Closures for Bottles and Jars and Methods of Affixing Same, of which the following is a specification, the principle of the invention being herein explained and the best mode in which I have 10 contemplated applying that principle, so as to distinguish it from other inventions.

The subject of the present invention is a closure for bottles, cans and the like, and is 15 designed to provide a tighter and more secure closure around the top of the receptacle. It has heretofore been the practice to introduce a thin strip of flexible packing material such as a rubber washer, between 20 the top of the receptacle and the cap. One objection to this method of securing a closure is that unless the cap is very securely fastened to the receptacle, there is so little pressure put upon the packing material that 25 it admits a small amount of air to the contents of the receptacle.

In the present invention I have provided a cap which is adapted to retain a packing strip between it and the side of the receptacle adjacent to the top. The construction 30 of the cap is such that considerable pressure is put upon the packing material in both a vertical and a horizontal direction, but as the material is held from expansion 35 in a vertical direction by means of the form of the cap, it is forced to expand laterally against the side of the receptacle, thus giving an absolutely air tight closure.

To the accomplishment of these and related 40 ends, said invention then consists of the means and steps hereinafter fully described and particularly pointed out in the claims.

The annexed drawing and the following description set forth in detail certain mechanism and one method of utilizing the same 45 embodying the invention, such disclosed means constituting, however, but one of various ways in which the principle of the invention may be used.

50 In said annexed drawing: Figure 1 is a view in perspective showing the cap in position on a receptacle; Fig. 2 is a central vertical section showing the cap when first applied; Fig. 3 is a similar section showing the 55 completed closure; Fig. 4 is a section show-

ing the cap about to be compressed by the dies; Fig. 5 is a section showing the cap when compressed; while Figs. 6 and 7 show a modification in construction.

In Fig. 1 there is shown a receptacle 1 which may be of any desired form, but is here shown to be a glass, of the type used to preserve jellies, etc. The cap consists of a top 2 provided with a downwardly extending flange 3 provided with an inturned bead 60 7 at its lower edge. The precise form of the bead is of little consequence so long as it is adapted to hold a gasket or strip 4 of flexible packing material between it and a horizontal shoulder 5 formed on the flange 3. 65 In some cases the packing material might be held between the bead and the top of the cap, dispensing with the shoulder 5. It will be readily seen that the form of the packing strip and the shape of the flange will necessarily be made to conform with each other, while the construction of the first-named element will be controlled to a large extent by the form of the receptacle. Extending 70 around the flange is an indentation or inwardly directed corrugation 6 which engages the packing strip and forces it into a tight and resilient engagement with the receptacle. 75

In Fig. 2, I show the cap and packing material as assembled when first placed on the receptacle. The flange is given an initial slight indentation which will cause a slight pressure on the packing material and will control the direction of lateral expansion of 80 the flange during the operation to be described hereinafter. In this way a very satisfactory closure can be secured as the packing strip is firmly held between the shoulder and the bead. 85

In Fig. 3 the cap is shown after the final compression. The indentation has been deepened by vertical compression and the packing material is forced against the receptacle, thus giving an absolutely air-tight 100 closure. The form of the cap before and after this final compression is best shown in Figs. 4 and 5 respectively. Dies 8 and 9 are used to engage the cap as shown, and the movement of these two dies toward each 105 other compresses the flange of the cap in a vertical direction. The result is, of course, to deepen the corrugation in the flange, the deepened corrugation or indentation being 110 inwardly directed and uniform around the

circumference of the flange by reason of the previously formed shallow corrugation which is deepened by the compression. The cap is now of less vertical depth than at first, as indicated by the dotted lines, and has a deeper indentation; consequently not only is the ring of packing forced bodily inward into contact with the outside of the receptacle neck by the compression of the 10 material of such ring in a vertical direction, but at the same time the deepening corrugation positively displaces or presses such material in a radially inward direction at all points. The ring of packing is thus put 15 under heavy pressure, which secures an airtight contact between the same and the flange on one side and the receptacle on the other. The final closure is thus made absolutely secure and is so tight that the cover 20 can be removed only with the aid of suitable tools.

It will be understood that for the bead 7, a simple curling in of the lower edge of the flange may be substituted, or in fact any formation that will serve to retain the underside of the ring of packing material when the flange is compressed. This is illustrated at 10 in Figs. 6 and 7, along with several other modifications. The latter include a 25 ledge or shoulder 11 formed integrally with the neck of the receptacle and spaced from the upper edge thereof a distance equal to the height of the flange after it has been compressed. In other words, this shoulder 30 subserves the same function as the lower die-member 9 in Figs. 4 and 5. A further modification consists in the omission of the shoulder 5, the upper edge of the packing ring 4 contacting directly with the under 35 face of the flat top of the cover. The relation of the parts before the compression of the flange is clearly shown in Fig. 6, while the succeeding Fig. 7 shows the effect of the 40 operation of the die 12 which corresponds with die 8 in the previously described arrangement.

Other modes of applying the principle of my invention may be employed instead of the one explained, change being made as regards the mechanism and steps herein disclosed, provided the means or steps stated by any of the following claims or the equivalent of such stated means or steps be employed.

55 I therefore particularly point out and distinctly claim as my invention:—

1. As an article of manufacture, a closure for receptacles of the character described, comprising a cover provided with a downwardly extending flange adapted to surround the mouth of the receptacle, said flange being formed with a relatively shallow encircling corrugation adapted to be rendered deeper upon being compressed and 60 having its convex face directed inwardly;

and an annular gasket located within said flange in line with such corrugation and adapted normally to slip over such receptacle-mouth, such corrugation being adapted upon being thus compressed to force 70 said gasket bodily inward into engagement with such mouth.

2. As an article of manufacture, a closure for receptacles of the character described, comprising a cover provided with a downwardly extending flange adapted to surround the mouth of the receptacle, said flange having its lower edge formed with an inturned bead, and, above such bead, with a relatively shallow encircling corrugation adapted to be rendered deeper upon being compressed in a direction at right angles to the cover and having its convex face directed inwardly; and an annular gasket located within said flange above the bead thereon and in 80 line with such corrugation, said gasket being adapted normally to slip over such receptacle-mouth and such corrugation being adapted upon being thus compressed to force 85 said gasket bodily into engagement with such mouth.

3. The combination with a receptacle of the character described, of a closure comprising a cover provided with a downwardly extending flange surrounding the mouth of said receptacle, such flange being formed with an encircling corrugation having its convex face directed inwardly; and an annular gasket located within said flange in line 90 with such corrugation, the latter being compressed so as to force said gasket bodily inward into engagement with such receptacle neck.

4. The combination with a receptacle of the character described, of a closure comprising a cover provided with a downwardly extending flange surrounding the neck of said receptacle, said flange having its lower edge formed with an inturned bead and, above such bead with an encircling corrugation having its convex face directed inwardly; and an annular gasket located within said flange above the bead thereon and in line with said corrugation, the latter being compressed so as to force said gasket bodily inward into engagement with such receptacle neck.

5. The method of affixing to a receptacle of the character described a closure comprising a cover provided with a downwardly extending flange adapted to surround the mouth of said receptacle, which consists in preliminarily forming such flange with a relatively shallow encircling corrugation adapted to be rendered deeper upon being compressed, such corrugation having its convex face directed inwardly; locating an annular gasket within said flange in line with such corrugation, said gasket being adapted normally to slip over the receptacle-mouth,

placing said cover with said gasket in place over such receptacle-mouth, and thereupon compressing such corrugation to force said gasket bodily inward into engagement with

5 such mouth.

6. The method of affixing to a receptacle of the character described a closure comprising a cover provided with a downwardly extending flange adapted to surround the
10 mouth of said receptacle, which consists in preliminarily forming such flange with a relatively shallow encircling corrugation adapted to be rendered deeper upon being compressed in a direction at right angles to
15 the cover, such corrugation having its con-

vex face directed inwardly; locating an annular gasket within said flange in line with such corrugation, said gasket being adapted normally to slip over the receptacle-mouth, placing said cover with said gasket 20 in place over such receptacle-mouth, and thereupon compressing such corrugation to force said gasket bodily inward into engagement with such mouth.

Signed by me, this 11th day of December, 25
1912.

HERBERT H. HULL.
